US00D511136S

(12) United States Design Patent (10) Patent No.: US D511,136 S
Hirschburger et al. (45) Date of Patent: * Nov. 1, 2005

(54) PORTABLE BATTERY CHARGING AND AUDIO UNIT

(75) Inventors: Wolfgang Hirschburger, Reutlingen (DE); Randall Coe, Chicago, IL (US); Steven W. Cole, Jr., Chicago, IL (US); Wing Hoi Ng, Hong Kong (CN)

(73) Assignee: Credo Technology Corporation, Broadview, IL (US)

() Term: 14 Years

(21) Appl. No.: 29/197,588

(22) Filed: Jan. 16, 2004

(51) LOC (8) Cl. 13-02

(52) U.S. Cl. D13/107

(58) Field of Search D13/106-108, D13/110; D14/188-189, 194-198, 204, 210, 251, 253; 320/105, 107-116; 455/347-351

(57) CLAIM

The ornamental design for a portable battery charging and audio unit, as shown and described.

DESCRIPTION

FIG. 1 is a front right perspective view of the present new design for a portable battery charging and audio unit; FIG. 2 is a front elevational view thereof, the rear elevational view being identical;

FIG. 3 is a right elevational view thereof, the left elevational view being identical; and,

FIG. 4 is a top plan view thereof, the bottom plan view being identical.

The broken lines showing various features of a portable battery charging and audio unit are for illustrative purposes only and form no part of the claimed design.
